UNITED STATES PATENT OFFICE.

CARL BOGROFF, OF ODESSA, RUSSIA.

STEAM-RADIATOR.

SPECIFICATION forming part of Letters Patent No. 605,775, dated June 14, 1898.

Application filed May 1, 1897. Serial No. 634,705. (No model.)

To all whom it may concern:

Be it known that I, CARL BOGROFF, a subject of the Czar of Russia, residing at Odessa, Haus Ralli, Empire of Russia, have invented 5 certain new and useful Improvements in Steam-Radiators, of which the following is a specification.

My invention relates to steam - radiators, and has for its object to produce a steam-radiator in which water is vaporized and confined in a closed cylinder for warming small rooms, such as bath-rooms, &c.

The invention consists of a reservoir, a steam-generator located therein, a radiator and condenser inclosing said reservoir and generator, and a tube leading from a source of heat through the generator and into an inner cylinder located within the radiator and communicating with the atmosphere.

Referring to the drawings, Figure 1 is a sectional side view of the steam-radiator, and Fig. 2 is a section on the line $x-x$ of Fig. 1.

Similar letters of reference indicate corresponding parts.

Referring to the drawings, the reservoir a is constructed of a cylindrical base supported a suitable distance above the ground upon feet d . The reservoir a is provided with a central opening in the bottom e , through which a tube or pipe f , open at both ends, is led. The cylindrical radiator k fits tightly within the reservoir a and rises from the bottom of said reservoir to a considerable height above the same. Inclosed within the radiator k is a smaller cylinder l , which extends downwardly into the same to the upper edge c of the reservoir a , as shown in Fig. 1. The cylinder l is provided with an opening q in the bottom p , through which the end of the tube f extends, and is also provided at its upper end with a flange m , by which it is secured to the radiator k , which flange m closes the top of the radiator, thus preventing the escape of steam or vapor therefrom. The upper end 45 of the inner cylinder l is closed by means of a cap or cover o , which is provided with perforations n for the escape of the products of combustion. The cylinder l divides the interior of the radiator into an annular space t and a larger space i below the space t and communicating therewith.

Within the reservoir a is fixed a cylinder

or block g , of cement or other suitable substance, which is provided with an opening concentric with but somewhat larger than the opening in the bottom e of the reservoir a . The tube f rises through the opening in the block g , leaving a small annular space h between the said tube and the block g . The block g is provided with channels in its under surface, by means of which constant communication is maintained between the small annular chamber or space h and the reservoir a . An ordinary lamp s is shown as the source of heat and is placed under the bottom e of the reservoir a . The burner r and chimney r' of the lamp s extend up into the tube f , as shown in Fig. 1. The block g divides the reservoir a into two annular chambers h and i , which are filled with water and which communicate below the block with each other. In this chamber i the water condensed in the upper part of the radiator k is collected and heated by the outer circumference of the cylindrical block g , whose inner surface is directly heated by the flame r of the burner s . The space h is so small that it contains practically only a film of water, which becomes quickly vaporized. The space h therefore forms the generator, while the outer space 80 serves for preliminarily heating the water, which when thus heated passes into the annular space h through the channels in the under surface of the block g to be again vaporized.

Having thus described my invention, what I claim is—

1. In a steam - radiator, the combination with a reservoir of a radiator communicating therewith, a generator located in said reservoir and provided with a central opening, a tube extending through said opening and of smaller diameter than the same forming an annular chamber communicating with said reservoir, and a source of heat communicating with said tube, substantially as set forth.

2. In a steam - radiator, the combination with a reservoir, of a radiator communicating therewith, a generator located in said reservoir and having channels in its under surface and provided with a central opening, a tube of smaller diameter located within said opening and communicating with a perforation in the bottom of the reservoir and a

source of heat communicating with said tube, substantially as set forth.

3. In a steam-radiator, the combination with a reservoir of a radiator communicating therewith, a generator located in said reservoir and channeled upon its under surface and provided with a central opening, a tube of smaller diameter located within said opening and communicating at its lower end with
- 5 an opening in the bottom of the reservoir, a cylinder located within the radiator and pro-
- 10

vided with an opening in its base through which the said tube extends, and a source of heat communicating with said tube, substantially as set forth.

In testimony that I claim the foregoing as my invention I have signed my name in presence of two subscribing witnesses.

CARL BOGROFF.
